UNITED STATES PATENT OFFICE.

JAMES H. DODDS, OF ST. PAUL, MINNESOTA, ASSIGNOR OF ONE-THIRD TO EDWARD T. McCALL, OF ST. PAUL, MINNESOTA.

ENGINE.

1,314,858.

Specification of Letters Patent.

Patented Sept. 2, 1919.

Application filed April 2, 1918. Serial No. 226,191.

To all whom it may concern:

Be it known that I, JAMES H. DODDS, a subject of the King of England, residing at St. Paul, in the county of Ramsey and State 5 of Minnesota, have invented a new and useful Engine, of which the following is a specification.

The device forming the subject matter of this application is an engine, and one object 10 is to provide novel means whereby water vapor is superheated and discharged into a turbine. Another object of the invention is to provide novel means whereby the vapor is forced to the heating means. A still further 15 object of the invention is to provide novel means for supplying liquid fuel and air under pressure to the mechanism whereby the water vapor is superheated.

Within the scope of what is claimed, 20 changes falling within the skill of a mechanic, may be resorted to, without placing the utility of the device in jeopardy or departing from the spirit of the invention.

In the accompanying drawings:—

25 Figure 1 shows in side elevation, an engine constructed in accordance with the invention; Fig. 2 is a cross section on the line W—W of Fig. 1; Fig. 3 is an end elevation wherein parts are broken away; Fig. 4 is an 30 elevation showing the main shaft and parts carried thereby; Fig. 5 is a longitudinal section; Fig. 6 is a cross section on the line Y—Y of Fig. 1; Fig. 7 is a cross section on the line Z—Z of Fig. 1; Fig. 8 is a top plan, 35 the line X—X indicating the cutting plane on which Fig. 5 is taken; Fig. 9 is a fragmental elevation showing a portion of the moistening means; Fig. 10 is a fragmental section taken through the fuel discharge 40 means; Fig. 11 is a sectional detail, enlarged from Fig. 5 and disclosing one of the valves; Fig. 12 is a cross section on the line 12—12 of Fig. 11.

In the drawings, the numeral 1 denotes a 45 tubular casing provided with inwardly extended flanges 5 and 5'. A head 2 is connected to the flange 5 by bolts 4, a head 3 being connected to the flange 5' by bolts 4'. The heads 2 and 3 are supplied with 50 porting brackets 8 having feet 6 and 7. The head 2 includes an exterior hub 9 which may be chambered as at 9', for cooling purposes. The hub 9 is recessed to form a bearing 8'.

The numeral 10' designates a tubular connection having a flange 11 secured to the head 3 the numeral 10 marking a hand hole cover

on the connection, and serving to give access to a valve 27, hereinafter mentioned. The tubular connection 10' is provided with a flange 11' carrying a bearing 12, there being 60 an exhaust port 12' at the top of the connection.

The flange 11' forms one head of a pump; the flange being connected by bolts 13, with a casing 17, and serving to retain a water 65 jacket ring 14 which is interposed between the flange 11' and one end of the casing 17. Intermediate its ends, the casing 17 is supplied with an annular partition 18, forming, within the casing, pump chambers 65 and 66. 70 A water jacket ring 15 is secured by bolts 16' to the outer end of the casing 17, the bolts retaining a head 16. Shafts 19 and 19' are mounted to rock in the upper portion of the casing 17 and are disposed parallel to the 75 axis of the casing. These shafts will be alluded to hereinafter. The head 16 is provided with a supporting foot 22.

The head 16 includes a bearing 21, and in the bearings 21 and 12, a main shaft 23 is 80 journaled, the inner end of the shaft having a bore 24, communicating with lateral openings 25 and 26 formed partly in the shaft and partly in members which will be alluded to hereinafter. On the inner end of the 85 shaft 23 is a flange 28. A valve 27 is seated in the end of the bore 24. The flange 28 is counter-bored and rotates in one end of the tubular connection 10', the counter-bore of the flange receiving an inwardly extended 90 flange 29 on one end of a hollow shaft 30', the flange 29 of the shaft 30' being bolted to the flange 28 of the shaft 23, so that these parts may rotate together. The shaft 30' is journaled at one end in the bearing 8' which 95 is fashioned in the hub 9 of the head 2. That end of the shaft 30' which is adjacent to the bearing 8' is provided with a plurality of openings 29' which permit the passage of an actuating fluid into one of two turbines, 100 hereinafter described. As shown in Fig. 4, the shaft 30' may carry a hand hole cover 29', giving access to the valve 27.

Two turbines are carried by the hollow shaft 30', the turbines including end members 30 and 32, individual to the turbines, and an intermediate member 31, common to both turbines. The end member 30 and the intermediate member 31 are connected by curved blades 34 and 33, the end member 105 32 and the intermediate member 31 being connected by curved blades 35 and 36, the

blades 35 and 36 being oppositely inclined with respect to the blades 33 and 34. The inner ends of the blades 33 are spaced from the hollow shaft 30', so as to effect a distribution of the actuating fluid when the latter passes through the openings 29' of the shaft 30' into the turbine of which the blades 33 and 34 form a part. The inner ends of the blades 35 of the other turbine are spaced in 5 a similar way from the shaft 30', it being observed that the shaft 30' has no openings adjacent to the inner ends of the blades 35 and corresponding to the openings 29'. Since the inner ends of the blades 35 are 10 spaced, as aforesaid, from the shaft 30', the exhaust may pass through an opening 37 in the end member 32 and in the head 3, into the tubular connection 10', and out through the exhaust opening 12'. The outer ends 15 of the blades 34 carry an annular covering 38, closing one turbine at its periphery. The intermediate member 31 is spaced peripherally from the casing 1, as shown at 39, the blades 36 being spaced as indicated at 20 35, from the casing 1. The outer ends of the blades 33 are spaced at 34' from the inner ends of the blades 34, and as indicated at 35', the outer ends of the blades 35 are spaced from the inner ends of the blades 36, 25 40 the spacing at 34' and at 35' serving to effect a distribution of the actuating fluid within the turbines.

The numeral 42 designates a bearing carried by a flange 41' secured by bolts 41 to 30 the hub 9, the flange 41' supporting a flue 50. Within the flue 50 is located an air chamber 52 communicating with a nozzle 54, the numeral 51 designating a torch body carrying a nozzle 53, the nozzles being disposed in converging relation. The flow of fuel into the torch body 51 is controlled by a needle valve 55 coöperating with a seat 55' in the torch body. The fuel traverses a fuel supply pipe 56 communicating with an oil chamber 52' in the torch body 51 and with the nozzle 53, by way of the seat 55'. The pipe 56 carries a cup 56' adapted to hold a priming charge whereby the oil in the chamber 52' may be heated at the time the engine is 35 started. A plug 56", mounted in the lower portion of the torch body 51, gives access to the chamber 52', so that the gas in the chamber may be ignited when the engine is started. There is a check valve 56', and a 40 valve 57' under the control of an operator, in the pipe 56. A pipe 57 communicates with the air chamber 52, a check valve 58 and a hand valve 59 being interposed in the pipe 57. The pipe 57 is adapted to convey 45 air to the nozzle 54, whereas the pipe 56 conveys fuel to the nozzle 53, a flame being produced at the free ends of the nozzles 53 and 54, within a tube 43 located within the tubular shaft 30' and spaced therefrom, one 50 end of the tube 43 being mounted in the part

42, and the other end of the tube carrying a closure plug 44. Said other end of the tube 43 is carried by a support 45 having feet 46 secured to the hollow shaft 30', the support, therefore, rotating with the shaft 30' 70 and rotating in the end of the tube 43. The feet 46 are spaced and form a spider which permits water vapor to pass, in a way to be described hereinafter, from the bore 24 of the shaft 23, past the valve 27, into the space 75 between the tube 43 and the tubular shaft 30', and into the turbine 33-34 by way of the openings 29 in the shaft 30'. The support 45 has an opening 47 in which slides a stem 48 carrying the valve 27, the valve being seated against the shaft 23 at one end of the bore 24, under the action of a compression spring 49 surrounding a portion of the stem and abutting against the valve and the support. 80

A wing 72 operates in the chamber 65 and a wing 73 operates in the chamber 66, the wings being located on opposite sides of the partition 18. The wings 72 and 73 are secured to the shaft 23 by keys, as indicated in 90 Fig. 7, one end of the wing 72 being journaled in the partition 18, as Fig. 5 will disclose. The wing 72 carries a cam 60, the wing 73 carrying a cam 61, as indicated in 95 Fig. 4. There is a chamber 63 in the cam 60, in communication with the opening 26 in the shaft 23, the cam 61 having a chamber 62 communicating with the opening 25 in the shaft 23. Communication is established between the chamber 62 and the chamber 66 100 by valves 64 in the cam 61, communication being established between the chamber 63 and the chamber 65, by similar valves in the cam 60. Air is admitted into the chamber 65 by means of air inlets 67, air being admitted into the chamber 66 by inlets 67', the inlets being covered with wire netting, shown at 100, in order to exclude foreign matter. Arms 68 and 69 are secured by screws 70'-70" to the shaft 19, arms 68' and 69' being secured by a like means to the shaft 19'. As shown at 71", the rings 14 and 15 are slotted to receive the arms 69 and 69', the casing 17 being similarly slotted to receive the arms 68 and 68'. A gate 70 is 110 carried by the arms 68 and 69 and is curved on an arc of which the shaft 19 is a center, the gate operating in a slot in the casing 17 and coacting with the cam 60. A similar gate 71 is carried by the arms 68' and 69' 115 and coöperates with the cam 61. The ring 15 is provided with a recess 74, the base of which is formed on an arc of a circle, the ring 14 being supplied with a similar recess. Wedges 73' are mounted to reciprocate for 120 adjustment on the bases of the recesses and operate beneath the ends of the arms 69 and 69' carried, respectively, by the shafts 19 and 19'. The inner ends of the gates 70 and 71 are rounded as shown at 70" so as to co- 125 130

- operate with the cams 60 and 61, the cams 60 and 61, together with the wings 72 and 73 operating on opposite sides of the partition 18 and between the partition and the rings 14 and 15. When the shaft 23 is rotated, air passes through the inlets 67 into the chamber 65 and is carried around by the cam 60 and is compressed against the gate 70. The air passes through the valves 64 in the cam 60 into the chamber 63. Air enters the inlets 71' and passes into the chamber 66. Here, the air is compressed between the cam 61 and the gate 71, the air passing through the valves 64 in the cam 61 into the chamber 62. When the cams 60 and 61 encounter the respective gates 70 and 71, the gates will be raised, the arms 68' and 69' rocking the shaft 19' and the arms 68 and 69 rocking the shaft 19.
- 20 The water jacket rings 14 and 15 carry means for operating the wedges 73' with respect to the arms 69 and 69', the wedges 73' having longitudinal slots 75, receiving bolts 74', holding the wedges on the bases of the recesses 74 in the rings 14 and 15. The wedges 73' have extensions, shown in Fig. 3 at 76, and pivoted at 77 to links 78' pivoted at 80 to crank arms 79 on a shaft 81 mounted to rock in lugs 82-82' on the rings 14 and 15 and on the members 11' and 16, the shaft being controlled by a centrally disposed lever 83 which is secured to the shaft. It will be seen that when the shaft 81 is rocked by means of the lever 83 the wedges 73' will be advanced and retracted with respect to the arms 69 and 69', and since both these arms and the gates 70-71 are connected to the respective shafts 19 and 19', the space between the gates and the cams 60-61 may be adjusted. In this way, the efficiency of the pumping mechanism may be regulated, and the engine may be stopped, since obviously, there will be a strong compression, for instance, between the cam 60 and the gate 70 if the end of the gate is in contact with the parts 72 and 60, whereas, the compression will be decreased, if the gate 70 is spaced slightly from the part 72, by the action of the corresponding wedge 73' and the arm 69.
- 50 Helical springs 84 and 84' are mounted on the top of the casing 17 and are held in place by keepers 85 and 85' fastened to the casing by screws 86 and 86'. The rear ends of the springs 84 and 84' engage the casing 17. The forward end of the spring 84 bears on a rod 87 which connects the arms 69 and 68, the forward end of the spring 84' bearing on a rod 87' which connects the forward ends of the arms 68' and 69'. The forward ends 60 of the springs 84 and 84' serve to thrust the gates 70 and 71 inwardly, to cause them to coöperate, respectively, with the wing and cam members 72 and 73.
- A pipe 88 extends above the openings or 65 inlets 67' and contains a hand valve 89, the horizontal portion of the pipe 88 having perforations 102 which discharge on the screens 100 of the inlets 67', water traversing the pipe 88 and being delivered on the said screens so as to moisten the air which passes into the chamber 66 by way of the inlets 67 and enters the chamber 62. The screens in front of the inlets 67 are not wet and consequently the air which passes into the chamber 65 and from thence into the chamber 63 is in a dry condition. Surplus water from the pipe 88 is received in a trough 90 and is carried away by a drain pipe 90'.
- A tank 91 is located beneath the pumping mechanism and is adapted to store liquid fuel of any kind. A portion of the dry air which is compressed in the chamber 65 is conveyed by a pipe 92, a T 95, and by the pipe 57, to the air chamber 52 and to the air nozzle 54. From the T 95, a pipe leads to the tank 91, and thus air pressure is supplied to the tank above the liquid fuel therein. Fuel leaves the tank 91, under air pressure by an L 95' and by the pipe 56 and thus is carried to the fuel chamber 52' and to the nozzle 53. In the pipe 92, a check valve 93 and a hand valve 94 are interposed.
- From the foregoing description taken in connection with the drawings, the operation of the device as now set forth, will be understood. At starting, the shaft 23 and the shaft 30', along with the turbines and other parts are rotated by hand, or by starters of the type commonly used in internal combustion engines. A slight pressure is thus created in the fuel tank 91, oil being supplied to the chamber 52' through the pipe 56, and air being supplied to the chamber 52 through the pipe 57. A priming charge is ignited in the cup 56², the plug 56³ is removed and the gas which has been created in the chamber 52' is ignited. The needle valve 55 is adjusted to regulate the supply of fuel, and a hot flame is produced within the tube 43, at the discharge ends of the nozzles 53 and 54, the tube being heated, and the products of combustion leaving by way of the stack 50.
- It has been pointed out hereinbefore that air is compressed in the chambers 62 and 63, a portion of the air, which has passed through the inlets 67', being moistened. The vapor thus produced enters the bore 24 of the shaft 23, passes the valve 27 under the suction of the turbine 34-33 and enters the space between the tube 43 and the hollow shaft 30'. When the vapor comes into contact with the highly heated tube 43, the vapor is superheated and converted rapidly into steam, pressure being transmitted to the blades 33 and 34 of one turbine through the openings 29'. Power thus is transmitted to the shaft 30' and to the shaft 23. The steam, having done its work, traverses the opening 39 and the space 40, and, being impelled by the blades 35 and 36 of the right

hand rotor in Fig. 5, leaves by way of the opening 37, the tubular connection 10' and the exhaust outlet 12'.

Having thus described the invention, what is claimed is:—

1. In an engine, a turbine; a hollow shaft carrying the turbine and discharging thereinto; a tube projecting into the shaft, means for heating the tube internally; a pump operatively connected with the shaft and discharging between the tube and the shaft; and means for supplying water vapor to the pump.

2. In an engine, a casing having an exhaust port; first and second turbines in the casing and communicating at their peripheries, the turbines having oppositely inclined blades, the second turbine discharging through the exhaust port; a hollow shaft carrying the turbines and discharging into the first turbine; a heating means in the hollow shaft; a pump operatively connected with the shaft and discharging between the heating means and the shaft; and means for supplying water vapor to the pump.

3. In an engine, a turbine; a hollow shaft carrying the turbine and discharging thereinto; a tube within the hollow shaft; an air conduit and a fuel conduit discharging into the tube; a fuel tank wherewith the fuel conduit communicates; a pump operatively connected with the shaft and comprising first and second parts, the first part discharging into the air conduit and into the fuel tank, and the second part discharging into the shaft about the tube; means for supplying

dry air to the first part of the pump; and means for supplying water vapor to the second part of the pump.

4. In an engine, a turbine; a hollow shaft 40 carrying the turbine and discharging thereinto; a pump shaft connected with the hollow shaft and having a bore communicating with the hollow shaft; a support within the hollow shaft and secured thereto; a valve 45 mounted on the support and seated in the bore of the pump shaft; a tube mounted at one end on the support; means for heating the tube; a pump on the pump shaft and discharging into the space between the tube 50 and the shaft, by way of the bore and the valve; and means for supplying water vapor to the pump.

5. In an engine, a turbine; a hollow shaft carrying the turbine and discharging thereinto; a fixed tube within the shaft; means for heating the tube internally; and means for supplying water vapor to the shaft exterior to the tube.

6. In an engine, a turbine; a hollow shaft 60 carrying the turbine and discharging thereinto; a fixed tube within the shaft; means for heating the tube internally; and means driven by the shaft for forcing water into the shaft exterior to the tube. 65

In testimony that I claim the foregoing as my own I have hereto affixed my signature in presence of two witnesses.

JAMES H. DODDS.
